(57) **CLAIM**

The ornamental design for an armrest plate as shown and described.

DESCRIPTION

FIG. 1 is a perspective view of an armrest plate showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an exploded view showing the armrest with an armrest;

FIG. 9 is an assembled view showing the armrest with the armrest; and,

FIG. 10 is an enlarged view of an indicated portion of FIG. 8.

The broken line portions of the armrest in FIGS. 1-10 represent unclaimed portions of the claimed design and form no part thereof. The broken line portions of the armrest in FIGS. 8-9 illustrate unclaimed environment and form no part thereof. The dot-dash broken lines in FIGS. 1 and 6-10 represent unclaimed boundary lines and form no part of the claimed design. The dot-dash-dot broken lines rendered in FIGS. 8 and 10 define the enlarged portions and form no part thereof.
